Martin E. Trolle, St. Paul, Minn., assignor to
Brown & Bigelow, St. Paul, Minn., a corpora-
tion of Minnesota

Application March 22, 1935, Serial No. 56,002

Term of patent 3½ years

To all whom it may concern:

Be it known that I, Martin E. Trolle, a citizen
of the United States, residing at St. Paul, county
of Ramsey, and State of Minnesota, have in-
vented a new, original, and ornamental Design
for a Combined Bottle Cap and Opener, of which
the following is a specification, reference being
had to the accompanying drawing, forming part
thereof.

Figure 1 is a perspective view of a combined
bottle cap and opener, showing my new design.

Figure 2 is a side elevational view.

Figure 3 is a bottom plan view.

Figure 4 is an end view.

I claim:

The ornamental design for a combined bottle
cap and opener as shown.

MARTIN E. TROLLEN.
